S. SMITH.

APPARATUS FOR CUTTING WEDGE BLOCKS AND DOYLE PINS

APPLICATION FILED MAY 21, 1999

936,744.

Patented Oct. 12, 1909.

Inventoz

Sheldon Smith,

By Franklin D. Long

Attorney

UNITED STATES PATENT OFFICE.

SHELDON SMITH, OF WOODLAND, CALIFORNIA.

APPARATUS FOR CUTTING WEDGE-BLOCKS AND DOYLE-PINS.

936,744.

Specification of Letters Patent. Patented Oct. 12, 1909.

Application filed May 21, 1909. Serial No. 497,539.

To all whom it may concern:

Be it known that I, SHELDON SMITH, a citizen of the United States, residing at Woodland, in the county of Yolo and State of California, have invented certain new and useful Improvements in Apparatus for Cutting Wedge-Blocks and Doyle-Pins; and I do hereby declare the following to be a full, clear, and exact description of the invention, such as will enable others skilled in the art to which it appertains to make and use the same, reference being had to the accompanying drawings, and to the letters and figures of reference marked thereon, which 15 form a part of this specification.

This invention relates to new and useful improvements in apparatus for cutting wedge-shaped blocks and doyle pins and comprises various details of construction, 20 combinations and arrangements of parts which will be hereinafter fully described and then specifically defined in the appended claims.

My invention is illustrated in the accompanying drawings, in which:—

Figure 1 is a perspective view of my improved apparatus. Fig. 2 is a vertical sectional view through the apparatus showing the manner of ejecting the blocks after being cut, and Fig. 3 is a detail view of the cutting knife. Fig. 4 is a detail perspective view of a punch and adapted to be attached to the apparatus.

Reference now being had to the details of the drawings by letter, A designates the table of the apparatus which is suitably supported and rising from said table are the two parallel guide bars B and B and intermediate said bars is the reciprocating 40 rod C having an elbow C' to which a T-shaped member D is fitted in any suitable manner, said member D being hollow and having a threaded wall for the reception of the threaded shank portion E of the 45 knife or of the threaded shell F which is adapted to carry a cylindrical cutter H for cutting doyle pins. Said reciprocating rod C has T-shaped guide arms J projecting therefrom and through which the rods B 50 pass for the purpose of guiding the rod C as the latter reciprocates by any suitable mechanism. Rising from said table is a standard L which has a recess L' upon one face thereof, the inner wall of said recess being inclined as shown. Said standard is 55 held in place by any suitable means, such

as screws N which pass through the shoudered portion of the standard and engage the table. The lower portion of the standard, made preferably of metal, has a lateral extension N' upon which the block to be cut is adapted to rest. 60

K designates a spring, one end of which is serrated, as at K', and extends through a slot formed in the wall of the recess L'. Said spring is positioned intermediate the bar C and the rear face of the standard L and, when a block O to be cut is placed within said recess L' and forced against the end of the spring, the latter will yield and, after a 70 wedge-shaped strip has been severed from the block O, said spring tends to throw the strip thus cut out of the recess in the standard L. 75

The cutting knife, designated by letter E', it will be noted is provided with two cutting edges, designated respectively by letters E² and E³, the former of which serves to cut a wedge-shaped strip from the block and the latter divides the wedge-shaped block 80 into two sections as the knife is moved downward against the block and held underneath the same. When it is desired to utilize the circular cutter in place of the knife for cutting the wedge-shaped strips, said knife E' is removed from the head carrying the same and the threaded shell F with the cylindrical outlined cutter fastened thereto substituted in place therefor. When the apparatus is adjusted for cutting the doyle pins, 85 the standard L and the spring may be readily removed from the table. 90

What I claim to be new is:—

1. In combination with a table, a vertical reciprocating rod passing therethrough, laterally projecting hollow T-shaped members projecting therefrom, fixed guide rods upon the table and passing through said T-shaped members, an elbow fixed to said reciprocating rod, a hollow threaded T-shaped shell 100 fixed to said elbow, and a cutting knife having a threaded shank portion engaging said threaded T-shaped member.

2. In combination with a table, a vertical reciprocating rod passing therethrough, laterally projecting hollow T-shaped members projecting therefrom, fixed guide rods upon the table and passing through said T-shaped members, an elbow fixed to said reciprocating rod, a hollow threaded T-shaped shell 105 fixed to said elbow, a cutting knife having a threaded shank portion engaging said 110

threaded T-shaped member, a standard mounted upon said table and having a recess in the face thereof, the wall of said recess being inclined and adapted to receive a block positioned underneath said cutting knife.

3. In combination with a table, a vertical reciprocating rod passing therethrough, laterally projecting hollow T-shaped members 10 projecting therefrom, fixed guide rods upon the table and passing through said T-shaped members, an elbow fixed to said reciprocating rod, a hollow threaded T-shaped shell fixed to said elbow, a cutting knife having a 15 threaded shank portion engaging said threaded T-shaped member, a standard mounted upon said table and having a recess in the face thereof, the wall of said recess being inclined and adapted to receive a block 20 positioned underneath said cutting knife, and a spring adapted to bear against a block held within said recess.

4. In combination with a table, a vertical reciprocating rod passing therethrough, laterally projecting hollow T-shaped members 25 projecting therefrom, fixed guide rods upon the table and passing through said T-shaped members, an elbow fixed to said reciprocating rod, a hollow threaded T-shaped shell fixed to said elbow, a cutting knife having a 30 threaded shank portion engaging said threaded T-shaped member, a standard mounted upon said table and having a re-

cess in the face thereof; the wall of said recess being inclined and adapted to receive 35 a block positioned underneath said cutting knife, and a spring extending through the inclined wall of said recess and having serrations at the end thereof adapted to engage a block held within the recess.

5. In combination with a table, a vertical reciprocating rod passing therethrough, laterally projecting hollow T-shaped members 40 projecting therefrom, fixed guide rods upon the table and passing through said T-shaped 45 members, an elbow fixed to said reciprocating rod, a hollow threaded T-shaped shell fixed to said elbow, a cutting knife having a threaded shank portion engaging said threaded T-shaped member, a standard having 50 a recess in one face thereof, the wall of said recess being inclined, the lower portion of said standard having a laterally extending projection, means for fastening the standard to the table, a spring passing 55 through said inclined wall of the recess and having teeth designed to yieldingly engage a block held within the recess and resting upon said projection.

In testimony whereof I hereninto affix my 60 signature in the presence of two witnesses.

SHELDON SMITH.
